WELL

Charles H. Hutto, Lubbock, Tex.

Application April 13, 1935, Serial No. 16,242

10 Claims. (Cl. 103—179)

My invention comprises a well of novel construction and a new method of constructing the same. Although my invention is especially for oil production, it is not confined to this use and 5 may be employed for pumping water or other subterranean fluids that it is desired to bring to the surface. In the application of my invention to oil wells it solves certain pumping problems not previously overcome by prior art devices and for 10 this reason the use of my new well construction results in a new method of pumping oil and this constitutes one phase of my invention.

I construct my well in a manner to convey the oil from the oil bed to the surface by passage 15 through the casing which is conventionally present in prior art wells. By this means I eliminate the expensive tubing which, in the prior art, is positioned inside the casing and is used for conveying the oil to the surface. The casing, constituting a passage larger in diameter than ordinary, presents less resistance to the work of pumping. In addition to these advantages I provide a simpler and less expensive method of dismantling and assembling the well than is known 20 in the prior art.

In the prior art the tubing, in addition to serving as a conveyor for the oil, functions as a connecting rod between the pumping engine walking beam and the pump piston. Therefore, in removing the pump elements it is necessary to disconnect the lengths of tubing and set them aside as they are progressively brought up. This requires expensive equipment that must be brought to the well, usually from a distance and at great 30 expense. A special crew, known commonly as the roustabout gang, is required for this purpose. The work of dismantling and repairing the well, as heretofore practiced, is time consuming and throws the well out of production for an appreciable length of time.

My pump permits the use of a cable connection between the piston and the pumping engine walking beam. Therefore, less expensive and more portable equipment can be used for dismantling and assembling the well and the operation 40 can be easily performed by the well attendant, commonly known as the pumper, in much less time than has been found necessary in prior art practice.

There are a number of novel features of my invention which permit me to accomplish these advantages.

I provide a seal between the casing and the subterranean pump. Thus, the oil is contained within the casing from the pump to the surface but it is confined within the pump from the level where it is joined to the casing downward into the oil bed. The seal will not permit the oil to pass 50 from the casing back into the oil bed between the

pump and the casing. This seal is of novel construction.

I also construct the pump as a plurality of unitary elements each readily and freely removable from the well apart from the other elements. 5 In dismantling the well, according to my invention, I do not endanger the future production of the well and I do this by the use of an element new in well construction which functions to contain the oil in the casing independent of the 10 pump and which I, therefore, term a container. Integral with the container I provide a standing valve. This standing valve also serves the additional purpose of being available and in operation in the event of the failure of the standing valve which I provide as part of the pump as in prior 15 art practice. This standing valve of the container is, for this purpose, auxiliary to the primary standing valve of the pump. This is important in that the failure of a standing valve 20 in the prior art practice causes the column of oil in the conveyor tubing to drop onto the oil bed, injure the bed and reduce its future production by creating a back pressure.

The pump elements are especially constructed 25 to facilitate assembling and dismantling the well and a novel tool, of a structure to cooperate with the specially constructed pump elements, contributes to this purpose.

The various advantages as hereinbefore stated 30 will be clear to those skilled in the art from the detailed description of the invention to follow when considered in conjunction with the accompanying drawings of which:

Fig. 1 presents a cross-sectional elevation of 35 the well with the new pump in position.

Fig. 2 is a cross-sectional view taken on line 2—2 of Fig. 1.

Fig. 3 is a cross-sectional view similar to Fig. 2, 40 taken on line 3—3 of Fig. 1.

Figs. 4 and 5 are cross-sectional views in elevation, similar to Fig. 1, showing the operation of the tool used in dismantling and assembling the well.

In Fig. 1 there is shown the bottom of an oil 45 well. In the construction of the well it was first drilled to the depth to be occupied by the casing 1. The casing 1, which can be of usual construction, was then positioned to extend from the surface of the oil field to a level above the oil bed 2 but near it within the limits of oil well construction. The casing was then sealed with cement 3 to prevent water or other fluids from flowing from the upper soil into the oil bed to impair it. The well was then dug from the lower extremity of the casing into the oil bed 2. The perforated liner 4 was then positioned to extend from the bottom of the casing 1 into the oil bed, as seen in Fig. 1. The perforated liner functions to strain the oil out of 50 55 60

the sand and permit it to pass into the pump. The well, as described thus far, may be of usual construction. In fact, my invention is applicable to wells of long use by simply replacing the prior art pump with my novel pump.

The well, in the condition described, is ready to be equipped with a pumping means for lifting the oil to the surface. The pump I use for this purpose consists of the working chamber, indicated generally by the reference numeral 5, and the piston 6. The piston I prefer to use includes a, so called, working valve 7, and, similar to common construction, it is one way in its action to give the oil passage through the piston out of the working chamber. However, instead of using the usual tubing for conveying the oil to the surface, I pump the oil directly into the casing as a passage to convey the oil to the surface. I use the cable 29 as the power connection between the pumping engine walking beam and the piston. Accordingly, I connect the piston to the cable 29 by means of the rod 30 which is large enough to cause the piston to fall of its own weight. As in common practice, the valve 7 opens on the down stroke of the piston to permit the passage of the oil, and closes on the up stroke of the piston to seal it for lifting the oil, at the same time drawing more oil into the working chamber.

The working chamber consists of a working barrel 8, which fits loosely in the casing 1 and the container 26 hereinafter described, and includes the cylinder 9 in which the piston works. At the top of the working barrel is the bell shaped guide 10 which is beveled as shown at 12 to direct the piston unimpaired into the cylinder when it is being lowered into the well to assemble the pump. The guide 10, on its outer periphery, provides a flange that overlaps the container. The bell shaped guide 10 is attached to the cylinder 9 by screw threads 13 or, instead of being attached directly to the cylinder, it may be joined to the cylinder by intermediate pipe to add length. This additional length is sometimes necessary to extend the working chamber from the casing, which is above the level of the oil bed, to a level within the limits of the oil bed because of the distance between the bottom of the casing and the oil bed. The intermediate pipe is of similar construction to the cylinder but its inner surface need not be polished.

It will be noted that, contrary to conventional construction, the cylinder is open at its upper end and thus the piston is unhindered and can be freely removed from the well without impairment for repair and replacement of packing without disturbing the rest of the pump. It will also be noted that the working barrel fits loosely in the casing 1 and the container 26 and occupies space entirely within the space described by the inside periphery of the casing 1 whereby it has free passage into operative position in the well and out.

Attached to the lower end of the cylinder 9, as by threads 14, is the standing valve, generally indicated by the numeral 15. It consists of the drum 16 with the valve seat 17 and the poppet 18. On the upstroke of the piston the poppet 18 lifts against the action of the spring 19 to permit the oil to pass into the cylinder 9. In operation, the poppet rides in the guide 20 which is perforated as shown in Fig. 3 to permit the passage of oil through the valve from below. On the downstroke of the piston the poppet 18 seats,

aided by the action of the spring 19, to seal the lower end of the working chamber.

The poppet is equipped with a flanged button 21 and the drum has a flange 23. These elements function in the assembling and disassembling of the well and will be discussed more at length hereinafter.

Between the working barrel and the casing I provide the fluid-tight packing seal 24, 25 which prevents the oil from passing below this level in the casing and positions the working chamber, which otherwise is suspended loosely in the container 26, stably within the well. When the well is in production there is a column of oil in the casing from this level to the surface of the field. The seal consists of two rings of rubber, lead or other pliable material which spreads under the weight of the working barrel. The lower ring 24 sets upon the container 26, the upper ring 25 fits around the bell shaped guide 10, which overlaps the container 26 for this purpose, and the two rings meet along the beveled surface 27, as shown. The working chamber, in position in the well, rests on the container 26 with the packing 24, 25 confined between the top edge of the container 26, the casing 1 and the flanged guide 10. The beveled surfaces 27 act to facilitate the spreading of the rings and also permit them to separate readily in disassembling the well.

I provide a container, indicated generally by the reference numeral 26, which functions to close the lower end of and contain the column of oil within the casing 1 when the pump 5, including the piston 6, and the working barrel 8 and the standing valve 15, are removed from the well. The container 26 fits loosely in the casing 1 and liner 4 and includes the tubing 26' which extends from the casing, which is at a level above the level of the fluid bed, to a level far enough within the limits of the fluid bed to permit the pump 5 to extend into the fluid bed. Attached to the tubing 26', below the lower extremity of the working barrel 8 and the standing valve 15, the tubing 26' being extended long enough for this purpose, I provide the standing valve 28 which, in addition to closing the lower end of the container, operates auxiliary to standing valve 15.

The auxiliary standing valve 28 is similar to the standing valve 15. It consists of the drum 16', valve seat 17', and poppet 18'. The poppet rides in the guide 20' and is equipped with the flanged button 21'. The drum 16' is provided with the flange 23'. The dimensions of the elements inside the drum 16', the inside dimensions of the drum itself and, especially, the dimensions of the button 21' and the flange 23' are the same as or similar to corresponding elements of the standing valve 15. This permits the use of the same tool for removing and applying either valve from or to the well.

The auxiliary valve is joined to the casing by tubing 26' and is sealed by means of fluid-tight packing rings 24', 25' which are similar to the rings 24, 25 and function in the same manner. The rings 24', 25' spread under the weight of the container 26, which fits loosely in the casing 1 and liner 4, to position the container stably within the well and form a seal to prevent the oil from passing from the casing between the casing and container into the oil bed when the pump 5 has been removed from the well.

Referring now to Figs. 4 and 5, the attention is directed to the tool indicated generally by the numeral 31. It comprises the rod 32, the dogs 34 and the hooked fingers 35. The dogs 34 are in

constant engagement with the springs 36 which tend to hold them extended outwardly in the position shown in Fig. 4. The springs are guided in the slots 37 of the shoulder 38 of the rod 32. 5 The dogs 34 are provided with cam surfaces 39 which engage the upper edge of the drum 16, as clearly seen in Fig. 4, to cause the dogs 34 to retract against the action of the springs 36 until they pass below the range of the flange or shoulder 23. The springs 36 then extend the dogs outwardly into latching engagement with the shoulder 23.

As the tool advances into the drum 16 the hooks 42 of the fingers 35 engage the button 21 and they spread until they fall beneath the flange or shoulder 41 in latching engagement therewith. The fingers 35 are pivoted at 43 and have the upwardly extending triggers 40 which extend into the paths of the dogs 34 and are actuated, when the dogs retract, to spread the hooks 42 to disengage them from the shoulder 41. As shown, the shoulder 38 extends below the dogs 34 to form a protecting apron 47 for the fingers 35. The apron 47 is provided with the beveled surface 45 which functions to guide the tool into the working barrel 8 by cooperating with the surface 12 and from the working barrel into the drum 16.

The tubing 46 fits loosely over the cable 20 and is so positioned whenever the tool 31 is attached to the cable. Whenever the tool is in the well in engagement with the standing valve, either 15 or 28, the tubing 46 can be dropped into the well where it falls to rest on the shoulder 38. In this 35 position it has actuated the springs 36 and thus has retracted the dogs 34 out of engagement with the shoulder 23 and the fingers 35 out of engagement with the flanged button 21. By this means the tool has been released from the standing valve 40 and can be drawn from the well leaving the standing valve in the well.

The well is constructed in this manner. Presuming that the well has been drilled and the casing 1, sealed with cement 3, has been positioned in the well and the perforated liner 4 positioned in the well. The well is now ready to be equipped with a pump. The well, in the condition stated, may be one newly constructed or one that has been operated according to prior art practice and is now to be equipped in accordance with my invention. The cable 29 is first passed through the tubing 46 and is then attached to the tool 31. The ring 25' is positioned on the container 26 and the ring 24' is positioned over it. The tool 31 is now attached to the valve 28 with the dogs 34 engaging the flange 23' and the hooks 42 engaging the button 21'. The tool is now lowered into the well carrying with it the lower standing valve 28 and the tubing 26' as a 60 unitary structure comprising the container 26.

The standing valve 28 will continue into the well until the ring 24' engages the top of the liner 4. The container 26 is made long enough to extend from the casing 1 to a level well within the limits of the oil bed so that the working chamber, in its position within the container, extends to a level within the limits of the oil bed. This is readily accomplished by using a standard size tubing. The weight of the container 26 and the standing valve 15' cause the rings 24' and 25' to spread to form a stable support for the container 26 and a fluid-tight seal between the container 26 and the casing 1.

Until the container 26 has been positioned in the well the tubing 46 has been held at the sur-

face. Now it is dropped into the well and it falls until it rests on the shoulder 38. In the latter position it has released the dogs from engagement with the flange 23' and the fingers 35 from engagement with the button 21'. This permits 5 the tool 31 to be brought to the surface leaving the container 26 stably in position in the well.

In a similar manner the working barrel and standing valve 15, as a unitary structure comprising the working chamber, are lowered into 10 the well. The ring 25 is positioned on the bell shaped guide 10 and the ring 24 is positioned over ring 25. The tubing 46 being positioned on the cable, the tool 31 is attached to the valve 15 with the dogs 34 engaging the flange 23 and the fingers 15 35 engaging the button 21. The valve 15 is then lowered into the well until the ring 24 rests on the top of the container 26. The weight of the working barrel assembly causes the rings 24 and 25 to spread confined between the top edge of the container 26, the casing 1 and the flanged guide 10 to position the working chamber stably within the well and form a seal between the working barrel and the casing which prevents oil from passing from the casing into the well outside the 20 25 working barrel. The tool is now removed from the valve 15 in the same manner in which it was removed from valve 28, by the use of the tubing 46.

When the tool is brought to the surface, the 30 piston is attached to the cable in its stead and the piston is lowered into the well. In its descent into the well the piston is guided into operating position in the cylinder by bell shaped guide 10. The cable is now rigged up for pumping and the well is ready to produce.

It will be noted that the cylinder above the piston is open to the casing. In the down stroke of the piston the valves 15 and 28 close under the action of the springs 19 and 19' and the oil in the working chamber passes through the valve 7 and through the piston 6 directly into and through the casing 1. On the up stroke of the piston the valve 7 seals and the piston lifts the oil in its passage through the casing 1 to the 40 45 surface. At the same time the piston draws oil into the working chamber 8 through the valve 15 and the valve 28 which lift against action of the springs 19, 19' respectively acting on the two valves. In the normal operation of the well but one standing valve is necessary. However, if the standing valve of the ordinary well fails, there is serious danger that the well be permanently injured. At any rate, the well must be dismantled for repair and this, as brought out more fully hereinafter, involves much greater danger of impairing the future production of the well. In the use of my pump, should one of the standing valves fail, the other valve would continue in operation and production of the well 50 55 60 would be maintained uninterrupted.

Should it ever become necessary to dismantle my new pump as, for example to make repairs, the cable is simply rigged for pulling the pump and the piston is pulled unhindered by and independent of the working chamber. In most cases this is all that is necessary to completely repair the pump because the most frequent repair necessary is the replacement of piston packing. This repair accomplished the piston can be replaced in the well, the cable rigged for pumping and the well is again ready for production with little trouble and at small expense and, more important, without a great hiatus in production.

In some cases when the piston has been re-

5 moved it will prove advisable to remove the standing valve 15 to determine the condition of the cylinder and the valve. This can be done with little trouble and loss of production. For 10 this purpose the piston is removed from the cable and the tool 31 attached. The tool is now lowered into the well and, guided by the bell shaped guide 15 and the surface 45 it will pass readily into the cylinder 8 and the drum 16. The cam surface 10 faces 39 of the dogs 34 engaging the top of the drum will cause the dogs to retract against the action of the springs 36. In the continued descent of the tool 31 the dogs 34 will extend outwardly and be in latching engagement with the 15 flange 23 and the fingers 35 will spread until the hooks 42 engage the flange 41 of the button 21.

15 The tool is now drawn up and the hooks 42 first lift the valve 15 from its seat 17 and relieve 20 the retarding action of the weight of the column of oil in the casing 1. In addition, the removal of the cylinder does not disturb the container 26 and its packing seal and the column of oil in the casing is not removed. In prior art wells, 25 the removal of the pump also removes the column of oil from the pump to the surface, or else it must be permitted to fall into the well directly onto the oil bed.

20 While the working barrel 8 is being pulled, it 30 will be noted, the lower standing valve 28 carries the load of the column of oil, and it is not permitted to fall onto the oil bed. If the oil is permitted to fall onto the bed, it sets up a back pressure which seals the sand and impairs the 35 future production of the well. This has been the cause of frequent injury to the wells of prior art practice.

25 If it is desired to remove the lower standing valve 28, this can be done without injury to the 40 well. The well is swabbed out, i. e., the oil is removed from the casing 1 to an extent that will not leave a heavy column of oil to fall onto the bed. It will be noted that the casing is free from 45 obstruction at this stage of the dismantling of the well and there is no great problem in swabbing the well. Enough oil remains in the casing to prevent the air from coming into contact with the bed when the lower standing valve 28 is removed.

50 In the prior art practice it will be noted that, when the well is dismantled for repair, the pump in its entirety, including the working barrel, the piston and the single standing valve, are removed as a unit. The connecting rod to the 55 piston constitutes the tubing that conveys the column of oil and there is a column of air in the casing. As the tubing is parted progressively into lengths to bring the pump to the surface, the column of oil is also brought to the surface and 60 the removal of the pump exposes the bed to the air. This causes a cooling of the bed with a resultant paraffining which lowers the future production of the bed. I eliminate any danger of the oil bed being exposed to air.

65 I claim:

1. A well comprising a casing extending from the surface of the field to a level only near to but above the level of the fluid bed for passage of the pumped fluid to the surface, a pump within the 70 well extending to a level within the limits of the fluid bed for pumping the fluid from the bed into and through the casing, a container to close the lower end of the casing so constructed as to prevent the passage of fluid from the casing into the fluid bed independent of the presence or

absence of the pump and to permit the passage of fluid from the fluid bed to the casing, said pump being so positioned relative to the container that it may be removed from the well without causing the container to release the column of fluid in the casing for passage from the casing into the fluid bed. 5

2. A well comprising a casing extending from the surface of the field to a level only near to but above the level of the fluid bed for passage 10 of pumped fluid to the surface, a container to close the lower end of the casing so constructed as to permit the passage of fluid from the fluid bed to the casing but to prevent the passage of fluid from the casing into the fluid bed and extending from the casing to a level within the limits of the fluid bed, a pump within the well 15 extending to a level within the limits of the fluid bed for pumping fluid from the fluid bed into and through the casing, means for removing the pump from the well, the pump being extended into the container and positioned in such a manner that the removal of the pump from the well may be effected without causing the container to release the column of fluid in the 20 casing for passage from the casing into the fluid bed. 25

3. A well comprising a casing extending from the surface of the field to a level only near to but above the level of the fluid bed for passage 30 of the pumped fluid to the surface, a container to close the lower end of the casing so constructed as to permit the passage of fluid from the fluid bed to the casing but to prevent the passage of fluid from the casing into the fluid bed and extending from the casing to a level within the limits of the fluid bed, a pump within the well 35 comprising a working chamber and a piston extending to a level within the limits of the fluid bed for pumping fluid from the fluid bed into and through the casing, means for removing the piston from the well independent of the working chamber, the working chamber comprising a cylinder open at its upper end to permit unhindered insertion and removal of the piston, 40 means for removing the working chamber from the well, the working chamber being extended into the container and positioned in such a manner that the removal of the working chamber from the well may be effected without causing the container to release the column of fluid in the 45 casing for passage from the casing into the fluid bed. 50

4. A well comprising a casing extending from the surface of the field to a level only near to 55 but above the level of the fluid bed for passage of the pumped fluid to the surface, a container to close the lower end of the casing so constructed as to permit the passage of fluid from the fluid bed to the casing but to prevent the passage of 60 fluid from the casing into the fluid bed and extending from the casing to a level within the limits of the fluid bed, a fluid-tight seal between the container and the casing, a pump within the well extending from the casing to a level within 65 the limits of the fluid bed for pumping fluid from the fluid bed into and through the casing and comprising a working chamber and a piston, means for removing the piston from the well independent of the working chamber, the working 70 chamber comprising a cylinder open at its upper end to permit unhindered insertion and removal of the piston, a packing between the working chamber and the casing to position the pump stably within the well, means for removing the 75

working chamber from the well, the pump being extended into the container and positioned in such a manner that the removal of the pump from the well may be effected without causing the container to release the column of fluid in the casing for passage from the casing into the fluid bed.

limits of the fluid bed, a fluid-tight seal between the casing and the container to prevent the passage of fluid from the casing to the fluid bed, a pump for pumping the fluid from the fluid bed into and through the casing and comprising a working chamber and a piston, the working chamber fitting loosely in the casing, extending from the casing into the container to a level within the limits of the fluid bed and comprising a cylinder fitting loosely within the container and open at its end to permit the unimpaired insertion and removal of the piston, a flange at the upper end of the cylinder overlapping the container and a packing confined between the upper edge of the container, the casing and the flange for resting the working chamber on the container in stable position within the well, means for removing the piston from the well independent of the working chamber, means for removing the working chamber from the well without disturbing the container and its seal, means for removing the container from the well, the means for removing the working chamber and the container being of similar dimensions to permit the use of the same tool for removing both elements.

5. A well comprising a casing extending from the surface of the field to a level only near to but above the level of the fluid bed for passage of the pumped fluid to the surface, a container to close the lower end of the casing so constructed as to permit the passage of fluid from the fluid bed to the casing but to prevent the passage of fluid from the casing into the fluid bed and extending from the casing to a level within the limits of the fluid bed, a pump within the well extending to a level within the limits of the fluid bed for pumping fluid from the fluid bed into and through the casing, means for removing the pump from the well, the pump being extended into the container and positioned in such a manner that the removal of the pump from the well may be effected without causing the container to release the column of fluid in the casing for passage from the casing into the fluid bed, means for removing the container from the well, the means for removing the pump and the container being similar in dimensions to permit the use of the same tool for removing both elements.

6. A well comprising a casing extending from the surface of the field to a level only near to but above the level of the fluid bed for passage of the pumped fluid to the surface, a container to close the lower end of the casing to prevent the passage of fluid from the casing into the fluid bed and comprising a tubing extending from the casing to a level within the limits of the fluid bed and a standing valve at the lower end of the tubing which opens to permit the passage of fluid from the fluid bed to the container and closes to prevent the passage of fluid back into the fluid bed, a pump within the well extending to a level within the limits of the fluid bed for pumping fluid from the fluid bed into and through the casing and comprising a working chamber and a piston, means for removing the piston from the well independent of the working chamber, the working chamber comprising a cylinder open at its upper end to permit unhindered insertion and removal of the piston and a standing valve at the other end of the cylinder, means embodied in the standing valve of the working chamber for removing the working chamber from the well, the working chamber being extended into the container and positioned in such a manner that the removal of the working chamber from the well may be effected without causing the container to release the column of fluid within the casing for passage from the casing into the fluid bed, means embodied in the standing valve of the container for removing the container from the well, the standing valves of the working chamber and the container being of similar dimensions to permit the use of the same tool for removing both elements.

7. A well comprising a casing extending from the surface of the field to a level near to but above the level of the fluid bed for passage of the pumped fluid to the surface, a container to close the lower end of the casing comprising a tubing fitting loosely within the casing and extending from the casing to a level within the limits of the fluid bed, a pump within the well extending to a level within the limits of the fluid bed for pumping fluid from the fluid bed into and through the casing, means for removing the pump from the well, the pump being extended into the container and positioned in such a manner that the removal of the pump from the well may be effected without causing the container to release the column of fluid within the casing for passage from the casing into the fluid bed, means embodied in the standing valve of the container for removing the container from the well, the standing valves of the working chamber and the container being of similar dimensions to permit the use of the same tool for removing both elements.

8. A well consisting of a casing and a subterranean pump, the pump comprising a working chamber within the space described by the inside periphery of the casing, the working chamber consisting of an upright cylinder open to the casing at its upper end, a piston and a first standing valve for passage of the oil into the cylinder, a fluid-tight seal between the working chamber and the casing to prevent the passage of oil from the casing into the oil bed, the standing valve, positioned at the lower end of the cylinder, forming a unitary structure with the cylinder, means embodied in this structure to facilitate its removal from the well as a unit, a second standing valve auxiliary to and below the first standing valve, operable simultaneous with but independent of it, the second standing valve forming a unit separate from the first standing valve and positioned within the space described by the inside periphery of the casing, a fluid-tight seal between the second standing valve and the casing to prevent the passage of oil from the casing into the oil bed, means embodied in the second standing valve to facilitate its removal from the well, the means for removing the first and second standing valves being of like construction to permit the use of the same tool.

9. A well consisting of a casing, a subterranean pump and a container, the pump being positioned within the space described by the inside periphery of the casing and comprising a working barrel, a piston and a first standing valve, the working barrel consisting of an upright cylinder open to the casing at its upper end, the first standing valve being positioned at the lower end of the cylinder to permit the passage of the pumped fluid into the cylinder and forming a unitary structure with the cylinder, means embodied in this structure to facilitate its removal from the well without disturbing the container, the container comprising a tubing between the pump and the fluid bed and a second standing valve auxiliary to the first standing valve and operable simultaneously with but independent of it, and a fluid-tight seal between the container and the casing.

10. In a well as claimed in claim 9, means embodied in the auxiliary standing valve to facilitate its removal from the well.
